MADELEINE KUSTERKO, OF YONKERS, NEW YORK.

GARMENT.

1,226,977.

Specification of Letters Patent. Patented May 22, 1917.

Application filed November 2, 1915. Serial No. 59,177.

To all whom it may concern:

Be it known that I, MADELEINE KUSTERKO, a citizen of the United States, and a resident of Yonkers, in the county of Westchester 5 and State of New York, have invented certain new and useful Improvements in Garments, of which the following is a specification.

My invention relates to an improvement 10 in garments, and particularly to cloaks or coats intended to be worn on the outside of the person; and has for its primary object to provide a coat or cloak which is designed especially for infants and other persons 15 unable to dress themselves, and which can be put on without forcing the sleeves of the garment lengthwise over the arms of the wearer; while at the same time having the appearance of a conventional coat or 20 cloak after the wearer dons the same and disposes the various parts into their proper positions.

The above and other objects and advantages of my invention will be made clear in 25 the following description taken in connection with the accompanying drawings, and be fully pointed out in the appended claim. I wish to have it understood, however, that the disclosure herein is illustrative only and 30 sets forth, but one embodiment of my invention; and that I reserve the right to modify the details thereof to the full extent which is permitted by the general meaning of the terms in which the claim is expressed. On the drawing:

Figure 1 is a front view showing the manner in which my approved coat is made; and

Fig. 2 is a view of my improved garment as the same appears when laid out open on 40 a substantially flat surface.

In the particular description of my invention I utilize the numeral 1 to indicate the body of my improved cloak or garment; the same being cut to encircle the wearer's 45 figure; and being divided in front as shown at 2 for this purpose. Any suitable fastening device, such as buttons and button holes or hooks and eyes, etc., may be employed along the edges 2 to join these edges to each other. The edges 2 extend from the bottom of the garment to the opening 3 for the neck; and from the sides adjacent the neck extend outward sleeves 4.

These sleeves 4 are divided along their 50 tops from the cuffs or the outer ends of the sleeves clear to the inner ends and further,

along the tops of the shoulders to the neck opening 3. This mode of cutting the sleeves and shoulders along the top is indicated at 5, and the upper parts of the sleeves and shoulders may have fastening devices, such as buttons and button holes or hooks and eyes, or any convenient means to enable the divided edges of the coat or cloak along the tops of the shoulders and sleeves to be secured together. 60

It will now be apparent wherein the utility and simplicity of my invention resides. In order to put on a cloak made as just described, the garment is unfastened in front 70 and also along the tops of the sleeves and shoulders; the edges of the sleeves and shoulders are next buttoned or fastened together, and then the garment may also be secured along the front 2; the finished effect will be 75 the same as a garment made in the ordinary way.

Such a garment is a highly desirable article for the wardrobe of an infant or other person unable to dress without aid. 80 It can be put on when the wearer is in almost any position with a great degree of ease and convenience. If the person is standing up, the sleeves only have to be buttoned or fastened over the arm and shoulder and then the garment secured in front. On the other hand if the garment is to be put on while the wearer is lying down, as when the cloak is to be used to envelop the 85 form of a child or baby, the garment is laid out flat and the front portions of the sleeves are turned downward, as indicated at the left of Fig. 1. The baby is then laid in the middle of the garment, which is folded over upon him; the sleeves can then be buttoned 90 or fastened together along the tops of the arms or shoulders and the garment secured along the front edges 2 in the usual way. 95

The garment is intended especially for infants, and it obviates the necessity of handling a baby's arms to the extent required by an ordinary coat. An infant's arms being tender, some care must be exercised in putting on a coat of ordinary make, to avoid injury or annoyance; but with my coat, no 100 such drawbacks are encountered. The cloak herein disclosed can be put on with so little trouble that, if asleep, the child does not even have to be waked; and no rumpling of the sleeves of the baby's dress is entailed by 105 the operation.

I also employ in connection with my im-

proved garment a collar 6, which is made large enough to have the form of a cape and long enough to bring its front edges close together adjacent the edges of the body of the garment 1. The cape can be secured, as by buttons, hooks, etc., at one or more points 8 in the back adjacent the edge of the opening 3, and the front pair of corners thereon can be provided with fastening strings or ribbons 7. When the garment is being put on, the front ends of the collar are turned upward to uncover the divided tops of the sleeves and shoulders. After the garment is put in place on the form of the wearer and the sleeves and shoulders buttoned together, the front ends of the collar are turned into the position shown at the right of Fig. 1 and they may be secured together by tying the ribbons 7 into a bow or other ornamental effect. It will be understood that the collar completely hides the seams and fastening devices along the tops of the sleeves and shoulders because it is made wide enough to extend from the end almost out to the ends of the sleeves. One or two terminal buttons at the outer ends of the sleeves may, however, be left exposed for ornament. After the collar has been turned down it would be impossible to distinguish the garment from an ordinary garment made with undivided sleeves, and the terminal buttons thus will pass for the ordinary buttons which are commonly secured at the outer ends of coat sleeves in order to make the same resemble cuffs.

Fig. 2 illustrates my improved garment as it appears when it is laid out open upon a bed, table or the like in order to put the cloak upon the form of a child or baby; and it likewise shows clearly how the parts of the garment are preferably cut in order to enable them to be fastened together to make the finished article. I can cut the back of the garment in one piece as indicated by the numeral 9; and the front will preferably comprise two pieces 10 secured to the back piece 9 by means of seams 11. These seams extend along the sides of the garment and the lower edges of the sleeves. The back piece 9 will be approximately T-shaped and provided with lateral extensions at the top corners to form the backs of the sleeves. As for the front pieces 10, they will be arranged side by side and will each have approximately the form of an inverted L, the lateral projections of which will form the front of the arms, as will be readily perceived. The upper inner corners of the front pieces 10 will be cut away to provide short curved edges 12 which are provided to make the opening 3. When the garment is laid out flat to dispose the body of an infant therein the upper parts of the side pieces will make flaps 13 which project inward slightly beyond the seams 11, and beneath

these flaps there will be triangular folds 14 extending outward to the divided edges 2. When the child or other person is laid upon the cloak 9 these flaps 13 must, of course, be lifted beneath the arms and then they can be turned up and smoothed out to cause the front and backs of the sleeves 4 to envelop the arms. If desired, the front parts of the sleeves may be turned down as in Fig. 1 and the front pieces 10 doubled over outward in order to open out the garment so as to make an approximately square fold of the front pieces of which the forward sides of the sleeves are constituted.

When the child or other person is laid down upon the garment the sleeves will, of course, be secured in proper position by means of the fastening devices 5 and the front of the garment will be buttoned or otherwise secured along the front of the edges 2. The forward corners of the collar 6 can then be turned down to cover the shoulders and tops of the sleeves in the manner above set forth.

The cloak or coat is therefore made of only three pieces; namely, the integral back-piece and the two front-pieces, permanently secured together; and the collar or cape, when put in place, completes the garment. By making the garment of the T-shaped back-piece and the L-shaped front-pieces, simplicity, cheapness in production, and adaptability to the purposes in view, without the loss of any advantages, are insured; and when these pieces are fastened together, the sleeve portions will be held so as to maintain the divided edges on top, in the most convenient positions for getting the garment on the child's arms and shoulders.

From the above it will be apparent that my improved garment is exceedingly simple and can be put on with much less effort and in much shorter time than coats or cloaks made in the ordinary way. After the same has been donned and the parts properly disposed it cannot be distinguished from a garment made in the conventional manner.

Having described my invention what I believe to be new, and desire to secure and protect by Letters Patent of the United States is:

A coat or cloak, including a body comprising a T-shaped back-piece having a lateral extension projecting from each side at one end, and providing the rear halves of a pair of sleeves, said back-piece having a recess with a curved edge in said end between said extensions, and a pair of inverted L-shaped front-pieces permanently secured to the side edges of the back-piece, and having portions forming the forward halves of the sleeves, permanently secured to the adjacent edges of the extensions so that the halves of each sleeve will be connected along their 125

lower edges, said L-shaped pieces having cut-away corners to combine with said recess to provide a neck opening, means for detachably securing the said portions to the 5 opposite edges of said extensions, so that the coat or cloak can be opened along the top of said sleeves from their outer ends up to said recess, and a collar to be fastened to the back-piece and having its opposite ends un-

secured to be capable of being turned up to 10 uncover the sleeves, or down to overlie the sleeves, said collar then extending breadth-wise nearly to the outer ends of the sleeves.

Signed at New York, in the county of New York and State of New York, this 25th 15 day of October, A. D. 1915.

MADELEINE KUSTERKO.
